SAND BAILER AND PERFORATOR CLEANER

Augustus B. Scott, Long Beach, Calif.

Application September 9, 1940, Serial No. 356,061

4 Claims. (Cl. 166—19)

This invention relates to well cleaning devices, and more especially to pump, sand bailers designed for use in connection with oil or other deep wells, and the invention has for its object to provide a bailer constructed in a manner to allow the ready passage therethrough of any fluid which may be standing in the bottom of the well as the bailer is lowered to remove sand or other material which may have accumulated in the hole.

Other objects and advantages will appear and be brought out more fully from the following specification, reference being had to the accompanying drawing, wherein

Fig. 1 is an elevation in central section of a bailer embodying my invention;

Fig. 2 is a sectional view taken along the line 2—2 of Fig. 1; and

Fig. 3 is a fragmentary view illustrating the rope socket.

Referring more particularly to the drawing, I show a well casing or liner 5 having a plurality of apertures 6 in which is a bailer bucket 7, having an interior cylindrical wall 8, a plurality of apertures 9 adjacent to the upper portion thereof and a head 10 suitably secured thereto as by screw threads or otherwise, head 10 having a central bore 11 adapted to receive a piston rod 12. Piston rod 12 is suitably secured to a connecting socket 13 by means of threads 13' and the lock nut 14. The socket 13 has an extension 14', to which is secured the rope 15, as illustrated in Fig. 3. A collar 16 is secured to piston rod 12 within cylinder 8 and is adapted to engage the lower side of head 10 during upward operation and lock nut 17 is secured to the lower end of piston rod 12 and supports a valve cage 18 which is mounted on the rod 12 and has a conical upper surface. A piston valve 19 having an internal lower conical surface adapted to engage with the upper conical surface of cage 18 is carried by cage 18 and is provided with an external piston ring recess 20 in which is a piston ring 21 and a plurality of passages 22 connecting between recess 20 and the interior conical surface of valve 19. Valve 19 has a plurality of radial grooves 23 in the upper portion thereof adapted to communicate with an axial bore 24 in the valve which merges with the conical surface of valve 19.

The operation of the invention should be clear from the foregoing description.

During the vertical upward reciprocation of piston rod 12, collar 16 and valve 19 will be carried to the dotted positions indicated in Fig. 1. The downward movement of valve cage 18 from

the dotted line position shown in the drawing will force the material to be raised past the conical surfaces of cage 18 and valve 19 and upwardly through bore 24 and passages 23 and raised by valve 19 and piston ring 21 upwardly past collar 16, which is provided with side wall clearance and upwardly through apertures 9 and 6 through the well casing.

From the foregoing, it will be clear that the device of my invention is adapted to pump sand, mud and shale without sticking and that production for oil, water or other wells will be greatly increased.

It will also be clear that by the operation of my invention, the perforations of the liner will be kept open by the pulsation action of the device, and also permits the oil or water to enter the well.

It will also be clear that a vacuum can be produced by high speed operation or it can be operated without vacuum at low speed.

It will also be clear that by the use of a bailer as constructed according to my invention, the bailer will not stick nor become lost in the well.

Having described my invention, what I claim is:

1. A bailer of the character described, comprising a bailer bucket having a closed upper end and openings in the walls thereof, a piston rod loosely passing through the closed upper end, a collar carried by the piston rod for limiting the upward movement of the piston rod in the bailer bucket, a valve cage carried by the lower end of the piston rod and having a conical outer surface, a valve having a conical inner surface loosely mounted on the conical surface of the valve cage, an annular recess in the outer periphery of the valve, a piston ring in said recess and of a width and thickness less than the width and depth of the recess, and passages in the valve leading from the recess to the conical surface of the valve.

2. A bailer of the character described, comprising a bailer bucket having a closed upper end and openings in the upper ends of the walls thereof, a piston rod loosely passing through the closed upper end, an annular collar carried by the lower end portion of the piston rod and spaced from the walls of the bailer bucket for limiting the upper movement of the piston rod, a valve cage carried by the lower end of the piston rod and having a conical outer surface, a valve having a conical surface loosely mounted on the conical surface of the valve cage and its upper end spaced from the piston rod, an an-

nular recess in the outer periphery of the valve, a piston ring in said recess and of a width and thickness less than the width and depth of the recess, and passages leading from the inner wall of the recess to the conical surface of the valve.

3. The combination with a bailer bucket of a piston rod, a valve cage carried by the lower end of the piston rod and having a conical outer face, a valve having a conical inner face loosely mounted on the conical face of the valve cage, an annular recess in the outer face of the valve and passages in the valve leading from the inner face of the recess to the conical face of the valve, and a piston ring in said recess and of a width and thickness less than the width and depth of the recess.

4. The combination with a bailer bucket of a piston rod, a valve cage carried by the lower end of the piston rod and having a conical outer face, a valve surrounding the piston rod and spaced therefrom and provided with a conical inner face loosely mounted on the conical face of the valve cage, an annular recess in the outer face of the valve and passages in the valve leading from the inner face of the recess to the conical face of the valve, and a piston ring in said recess and tightly engaging the bore of the cylinder and of a width and thickness less than the width and depth of the recess.
